UNITED STATES PATENT OFFICE.

GEORGE LONDRESS AND LEYLAND ROGERS, OF CLARKSBURG, WEST VIRGINIA.

ZINC-FURNACE

1,213,922.

Specification of Letters Patent. Patented Jan. 30, 1917.

Application filed June 27, 1914, Serial No. 847,735. Renewed March 4, 1916. Serial No. 82,268.

To all whom it may concern:

Be it known that we, GEORGE LONDRESS and LEYLAND ROGERS, citizens of the United States, residing at Clarksburg, in the county of Harrison and State of West Virginia, have invented certain new and useful Improvements in Zinc-Furnaces, of which the following is a specification.

The present invention resides in improvements in zinc dross refining furnaces.

An object of the invention is the provision of a zinc dross refining furnace which is designed to be constructed from fire-brick or other similar material, so braced and reinforced, as to prevent any disintegration of the same, therefore insuring the long life thereof.

Another object of the invention is the provision of a furnace such as described having a plurality of fire boxes and a spiral flue in communication therewith.

A further object of the invention is the provision of a zinc dross refining furnace having a fire box and chamber into which dross is placed to be refined.

Still another object of the invention is the provision of a zinc dross furnace having a series of fire boxes over which is a chamber for receiving the dross to be refined, the said fire boxes having a spiral flue surrounding the same, the said dross chamber having an opening therein through which refined zinc can be discharged and a second opening extending above the first opening from the dross chamber into a condenser for permitting vapors or oxid arising from the dross to pass into the condenser for condensation.

A still further object of the invention is the provision of a zinc dross refining furnace which will be comparatively simple, and inexpensive to build, reliable and efficient in use, and readily operated, it being understood in this connection that various minor changes in the specific details of construction can be resorted to within the scope of the appended claims, without departing from or sacrificing any of the advantages of the invention.

With the above and other objects in view this invention resides in the novel features of construction, formations, combinations, and arrangements of parts to be hereinafter

more fully described, claimed and illustrated in the accompanying drawings, in which:

Figure 1 is a longitudinal sectional view taken through our invention. Fig. 2 is a front elevation thereof with the upper portion of the stack broken away. Fig. 3 is a transverse sectional view taken on the line 3-3 of Fig. 1.

Referring to the accompanying drawings by similar characters of reference, throughout the several views, the numeral 5 designates generally our improved zinc dross refining furnace which consists of a dross heating chamber or compartment 6 which is preferably of elliptical cross sectional formation, as clearly shown in Fig. 3, the same being surrounded by a rectangular shell 7 connected thereto by the spiral web 8, the convolutions of which extend transversely of the said compartment 6 providing a spiral flue 9 which extends from the fire boxes 19 and communicates through a passage 10 to the stack 11 through which particles of combustion may escape.

The above mentioned fire boxes are shown only in conventional form as their structure has no bearing upon the invention. It will be seen that the fire boxes are provided at the lower sides of the convolutions of the spiral flue and that there is one fire box in each of said convolutions. It will be seen that the products of combustion from each fire box passes through the flue, taking up the products of combustion from the next succeeding fire box and so on through the entire length of the apparatus until passing out through the stack 11.

The compartment 6 is closed by front and rear end walls 12 and 13, the former of which is provided with a suitable opening 14 through which dross can be placed in the compartment 6. This opening 14 is closed by a door 15. The compartment 6 and its surrounding shell 7 are braced by the upper and lower channel irons 16 and 17 and the spaced vertical channel irons 18.

The fire boxes 19 as shown in conventional form only and are located in spaced relation to each other, below the dross chamber 6, and connect with the lower sides of the convolution of the spiral flue 9. These fire boxes 19, also serve as cleanout passages for

the flue 9, and are provided with the usual openings or door ways 19.

A downwardly inclined discharge passage 29 extends from the dross compartment 6 through the wall 13 and provides a means whereby the zinc upon being converted to a molten state will run down the lower inclined side 30 of the compartment 6, through this passage 29 into the pots or kettles 27, which when filled can be removed as desired, and at any desired temperature. These kettles 27 are supported in any suitable manner, one form of support being indicated at 20', which includes the base 20 having extending therefrom the opposite vertical end walls 21 and 22 provided with shoulders 26 upon which and upon the upper edges of the walls 28, the kettles 27 rest. Located directly under the passage 29 is a second passage 40 communicating with the extreme right-hand fire box. This passage 40 is adapted to heat the passage 29 to prevent the metal flowing through said passage 29 from becoming chilled.

25 An extension 25 projects from the rear wall 13 of the furnace and is braced by a bracket 31. This extension is formed with an outwardly and downwardly inclined passage 32 which enters the open air above the rearwardly extending lip 34 of the said extension 25. Any vapors arising from the dross contained within the compartment 6 will pass into this passage 32 where they will be condensed and directed to flow over the end of the lip 34 and into the pots or kettles 27.

From the foregoing description taken in connection with the accompanying drawings, which form a part of this application, it will be manifest that a dross zinc furnace is provided which will fulfil all the necessary requirements thereof.

What is claimed is:

1. A zinc dross furnace comprising a series of fire boxes, a dross compartment and a spiral flue surrounding said dross compartment and communicating with and connecting each of said fire boxes.
2. In a zinc dross furnace, a series of fire boxes, a dross compartment having upper and lower discharge passages extending

through end wall thereof and a spiral flue surrounding said dross compartment.

3. A zinc dross furnace comprising a series of fire boxes, a dross compartment having upper and lower discharge passages extending through one end thereof, a stack for said furnace and a spiral flue surrounding said dross compartment and communicating with the fire boxes and stack. 55

4. In a zinc dross furnace such as described, a dross compartment, a plurality of fire boxes located below said compartment, a stack extending from said furnace, and a spiral flue surrounding the dross compartment and communicating with said stack. 60

5. In a zinc dross furnace, a dross compartment, a plurality of fire boxes located beneath said compartment, a spiral flue surrounding said compartment and in communication with the fire boxes, a stack extending from the furnace and communicating with said flue, a spelter box at one end of the furnace, the bottom of said dross compartment being disposed on a slant sloping 70 toward the spelter box, a plurality of removable kettles located in the spelter box, one wall of the furnace having an opening sloping from the lower wall of the dross compartment into the spelter box, and a second 80 opening sloping downwardly from the upper wall of said dross compartment to the spelter box. 75

6. A zinc dross furnace, comprising a dross compartment, a spiral flue surrounding said dross compartment, and a plurality of fire boxes, one connected to and communicating with each convolution of said spiral flue. 85

7. A zinc dross furnace, comprising a dross compartment, a spiral flue surrounding said dross compartment, and a plurality of fire boxes, one connected to the lower side of each convolution of said spiral flue and communicating therewith. 90

In testimony whereof we affix our signatures in presence of two witnesses.

GEORGE LONDRESS.
LEYLAND ROGERS.
